UNITED STATES PATENT OFFICE.

ARTHUR THOMAS MART, OF BROOKLYN, NEW YORK.

DESIGN FOR TILING.

SPECIFICATION forming part of Design No. 17,387, dated June 14, 1887.

Application filed April 16, 1887. Serial No. 235,124. Term of patent 3½ years.

To all whom it may concern:

Be it known that I, ARTHUR THOMAS MART, a subject of the Queen of Great Britain, residing at Brooklyn, in the county of Queens, State 5 of New York, have invented and produced a new and original Design for Tiling, of which the following is a specification, reference being had to the accompanying photograph, forming part thereof.

10 The leading feature of my design consists of the representation of a pair of winged beasts of the cat kind, regardant, lettered B B. Between these beasts there is a medallion representing a female head on a background consisting of a shell, marine animals, and leaves, 15 as shown at A, while in rear of the beasts there is an ornamental scroll-work of leaves, as shown at C C.

I claim—

The design for tiling, consisting of the winged 20 beasts, regardant, B B, the medallion A, and the scroll-work of leaves C C, as shown and described.

ARTHUR THOMAS MART.
